UNITED STATES PATENT OFFICE.

WILLIAM A. DOBLE, OF SAN FRANCISCO, CALIFORNIA, ASSIGNOR TO MAY E. DOBLE, OF ALAMEDA, CALIFORNIA.

IMPACT WATER-MOTOR.

No. 896,442.

Specification of Letters Patent.

Patented Aug. 18, 1908.

Application filed March 7, 1906. Serial No. 304,695.

To all whom it may concern:

Be it known that I, WILLIAM A. DOBLE, a citizen of the United States, residing at San Francisco, in the county of San Francisco and State of California, have invented certain new and useful Improvements in Impact Water-Motors, of which the following is a specification.

My invention relates to impact water motors and to that class of such motors where a main and a compensating valve coöperate to secure the desired variations in the action of the jet without any undue increase of pressure in the casing from which the water is supplied to the jet, and my invention consists in certain lever connections for securing the desired relative changes in position of the valves as fully set forth hereinafter and as illustrated in the accompanying drawings, in which—

Figure 1 is a sectional elevation of sufficient of an impact water motor apparatus to illustrate my invention; Fig. 2 is an end view of the parts shown in Fig. 1; Fig. 3 is a sectional elevation in which some of the connected parts are modified.

The casing A of any suitable construction has a nozzle 1, the jet from which is controlled by a valve 5 and is directed against the usual impact wheel X, and in order to prevent any undue increase of pressure within the casing from the sudden closing of the nozzle 1 and preserve the character of the jet, I make use of a compensating device consisting of a discharge port from the casing A which may be a nozzle 2 and a valve 8, and with these parts are combined means whereby to secure a slip or lost motion in the connections so that the valve 8 is opened only after the valve 5 has completed about three-fourths of its closing movement. As a result, the normal variations of position of the valve 5 to compensate for changes of load in operation are effected independently of the compensating device, the latter, however, coming into operation in order to prevent an increase of pressure in the casing when the valve 5 is carried beyond its normal position in closing. These main features are fully set forth in my application for Letters Patent No. 205,606.

My present invention relates particularly to devices for controlling the relative movements of the two valves, in the form of levers and connections therewith. As shown in Figs. 1 and 2, the valve stem 7 is connected with a pair of toggles 65 and the valve stem 11 with a pair of toggles 67, and a lever or arm 62 upon a rock shaft 40 turning in bearings of the frame of the machine is connected by a link 64 with the toggles 65, while an arm 63 on said shaft is connected by a connecting rod H with the toggles 67. The movements of the lever or arm 62 are imparted synchronously to the valve 5, but the connection H between the operating lever of the main valve and the compensating valve, is so constructed as to allow of a certain amount of slip or lost motion securing or permitting the limited movement of the main operating lever in closing the main valve, without effecting any change in position to open the compensating valve.

The connections between the lever and the compensating valve may be of different constructions. As shown in Fig. 1, the rod 66 is in two sections, one connected with a yoke 69 in which the other slides to an extent limited by a collar 70, and a spring 71 between the collar and yoke allows the upper portion 80 of the rod to slide in the yoke compressing the spring after the valve 8 closes its port and when the valve 5 is opened, and also holds the valve 8 in its closed position until the valve 5 has completed the major portion 85 of its closing movement when the contact of the collar 70 with the yoke will draw upward the toggles 67 and open the discharge or nozzle 2.

It will be seen that by the use of the toggles, I not only secure the advantage resulting from increasing leverage and greater power in operating the parts, but I also avoid abrupt and sudden movements of the valve which would tend to occasion objectionable and sudden variations in pressure in the casing.

The lever or arm 62 may be operated in any suitable manner, but as shown, is connected by a link 61 with a pivoted arm 60 which is connected to the piston rod 22 of a motor M, the movements of which are con-

trolled by a governor, as for instance, the well known Lombard governor. By this means, it is practicable to apply the necessary power to operate the operating lever 62 and its connected parts, while the governor itself exerts only the power requisite to operate the control device of the motor.

In the construction shown in Fig. 3, there is a lever connection between the parts but 10 without the use of toggles, the lever 62 being connected by a link to the end of the stem 7 of the valve 5 and having shoulders 77 and 78 between which slides a spool 75 having a circular recess receiving the forked ends of a 15 lever 72 connected at the other end to the stem of the valve 8. A spring 79 is arranged between the collar 77 and the spool 75 and the parts are so adjusted that during the normal movements of the valve 5, the spring 20 79 permits the stem 7 to move independently of the spool, the valve 8 remaining in a closed position. When, however, the valve 5 is carried to the left beyond about three-fourths of its travel in closing, the contact of 25 the collar 78 with the spool will carry the latter to the left and open the port controlled by the valve 8, the latter closing as the valve 5 is again moved to open its port and being held closed by the pressure of the spring 30 which, however, does not interfere with the further movement of the valve 5 to the right or its reciprocation under normal variations to compensate for variations in load and to 35 change the force of the jet thrown against the impact wheel X.

As in the construction of Figs. 1 and 2, the arm 62 may be shifted by the action of the motor M of the governor.

While I have referred to the action of the 40 compensating device as occurring during about the last quarter of the travel of the main valve, it will be understood that the extent of independent movement of the main valve will vary with circumstances, being 45 always sufficient to prevent reactions or shocks resulting from suddenly retarding the velocity of flow of water in the supply pipe.

It will be evident that as the main valve opens, there will be a closure of the discharge 50 but at such a rate as to prevent shocks.

I do not herein claim broadly the combination of the two nozzles and valves and actuating means as set forth in my aforesaid application Serial No. 205,606.

Without limiting myself to the construction and arrangement shown, I claim—

1. In an impact water motor the combination with a wheel provided with radial blades, a jet nozzle and valve within the same, a 60 compensating nozzle and valve, and lever connections between the two valves in which a lost motion is provided to allow the main

valve to close to about three-fourths its total extent before opening the compensating valve.

65

2. In an impact water motor, the combination of a jet nozzle and valve, a supplemental or compensating nozzle and valve, and lever and connections between the two valves all arranged to insure the opening of 70 the compensating valve only during about the last quarter of the closing movement of the main valve.

3. In an impact water motor, the combination of a jet nozzle and valve, a supplemental 75 or compensating nozzle and valve, toggles connected with the stems of the two valves, and a lever and connections for operating the toggles, substantially as set forth.

4. In an impact water motor the combination with a wheel provided with radial blades, a jet nozzle and valve within the same, a compensating nozzle and valve, and lever connections between the two valves in which a lost motion is provided to allow the main 80 valve to close to about three-fourths its total extent before opening the compensating valve, and a motor connected to operate said connections.

85

5. In an impact water motor the combination with a wheel provided with radial blades, a jet nozzle and valve within the same, a compensating nozzle and valve, and lever connections between the two valves in which a lost motion is provided to allow the main valve to 90 close to about three-fourths its total extent before opening the compensating valve, a motor connected to operate said connections, and a governor for said motor.

95

6. The combination of the casing, its nozzles, main and supplementary valves, and toggles, of a lever, and connections between the same and said toggles to operate the latter, substantially as set forth.

7. The combination with the casing, its 105 nozzles, main and supplementary valves, and toggles, of a lever, and connections between the same and said toggles to operate the latter, with means whereby the supplementary valve is opened as the main valve is closed, 110 substantially as set forth.

8. The combination with the wheel of an impact water motor, of a casing having a nozzle arranged to direct a jet against the wheel, a main control valve within the said nozzle, a discharge port and valve therefor, and connections between the two valves in which a lost motion is provided, for the purpose set forth.

9. The combination of the casing, main 120 and compensating nozzles and valves, lever connections for operating the main valve, and connections between the lever and compensating valve including a two part connecting

rod or link permitting a limited movement of one part independently of the other, substantially as set forth.

10. The combination with the wheel of an impact water motor, of a casing having a nozzle arranged to direct a jet against the wheel, a main control valve within the said nozzle, a discharge port and valve therefor, connections between the two valves in which a lost

motion is provided, and a motor, a lever operated thereby and connections between the said latter lever and the main valve.

In testimony whereof I affix my signature in presence of two witnesses.

WILLIAM A. DOBLE.
